UNITED STATES PATENT OFFICE

139,180

DESIGN FOR A COMBINED CHAIR,
OTTOMAN, AND HAIR DRIER

Frank La Foriyes, Rockford, Ill.

Application June 3, 1944, Serial No. 113,851

Term of patent 14 years

(Cl. D15—3)

To all whom it may concern:

Be it known that I, Frank La Foriyes, a citizen of the United States, residing at Rockford, in the county of Winnebago and State of Illinois, have invented a new, original, and ornamental Design for a Combined Chair, Ottoman, and Hair Drier, of which the following is a specification, reference being had to the accompanying drawings, forming part thereof.

In the drawings:

Fig. 1 is a side elevational view of a combined chair, ottoman, and hair drier showing my new design, the other side being substantially a counterpart;

Fig. 2 is a perspective view, and

Figs. 3, 4, and 5 are diagrammatic sections on the lines 3—3, 4—4, and 5—5 of Fig. 1, respectively, showing contour lines to indicate the curvature of the back wall of the housing at the three levels indicated by the section lines.

I claim:

The ornamental design for a combined chair, ottoman, and hair drier, substantially as shown and described.

FRANK LA FORIYES.
